United States Patent

Des. 235,782
Patented July 8, 1975

235,782

TREE ORNAMENT

Roger L. Martin, San Jose, Calif., assignor to Container Corporation of America, Chicago, Ill.

Filed Jan. 28, 1974, Ser. No. 436,873

Term of patent 14 years

Int. Cl. D11—02

U.S. Cl. D29—1 B

FIG. 1

FIG. 2

FIG. 3

FIG. 5

FIG. 4

FIG. 1 is a perspective view of a tree ornament, showing my new design;

FIG. 2 is a front elevational view thereof;

FIG. 3 is a side elevational view thereof;

FIG. 4 is a rear elevational view thereof; and

FIG. 5 is a bottom plan view thereof, the wings being omitted for ease of illustration.

I claim:

The ornamental design for a tree ornament, as shown.
